CLAIM

The ornamental design for a cap for a container, as shown and described.

DESCRIPTION

FIG. 1 is a top view of the cap for a container;
FIG. 2 is a bottom view of the cap for a container;
FIG. 3 is a side view of the cap for a container;
FIG. 4 is a perspective view of the cap for a container; and,
FIG. 5 is a perspective view of the cap for a container and an associated container.

The broken line showing a container is for illustrative purposes only and forms no part of the claimed design.
